MATCH CASE

Robert D. Kirkpatrick, Los Angeles, Calif.

Application January 13, 1956, Serial No. 558,961

7 Claims. (Cl. 67—7)

2

by which the entire operation of lighting the match may be accomplished in one hand, leaving the other hand free for whatever purpose may be desired.

Another object of the invention is to provide such a means which is safe and effective in its operation and which eliminates the necessity of discarding a used or burned match.

Another object of the invention is to provide a means and mechanism by which the lighting of a match may be accomplished by a single digital movement instead of the four usually required with conventional devices such as book matches.

A particular object of the invention is to provide means for advancing a plurality of radially mounted matches in a match case and which is capable of being operated in one hand to simultaneously ignite a match and to move it into position for use in the match case.

Other objects and advantages of the invention will be clear from the following description and from the drawings, in which:

Fig. 1 is a view in perspective of a match case embodying the invention, showing the manner in which it might be manipulated in one hand;

Fig. 2 is a view in section and elevation of the device of Fig. 1 taken from a point just behind the front cover of the device;

Fig. 3 is a view in elevation of the front cover of the device of Fig. 1 taken from the rear;

Fig. 4 is a view in section along the line IV—IV of Fig. 3;

Fig. 5 is a fragmentary view similar to Fig. 2 showing a modified form of striking surface;

Fig. 6 is a view in perspective of a further modification embodying the invention;

Fig. 7 is a fragmentary view in top plan of the device of Fig. 6;

Fig. 8 is a view along the line VIII—VIII of Fig. 7;

Fig. 9 is a view similar to that of Fig. 6 of a still further modification embodying the invention;

Fig. 10 is an enlarged perspective view of the advancing lever of Fig. 9;

Fig. 11 is a like view of a modified form of advancing lever; and

Fig. 12 is a top plan view of a modified device comprising in combination several units similar to the ones illustrated, for example, in Figs. 1 to 4.

Referring to the illustrative apparatus of the drawings, 29 indicates a match case of inexpensive construction such as cardboard, pasteboard or other suitable material, capable of being held in one hand in accordance with the invention. Preferably the case 20 is substantially disk-shaped and may be fabricated from two substantially cylindrical side or cover portions 22 and 24 secured to a thin cylindrical peripheral portion 26 by glue, staples or other suitable means. As best seen in Fig. 1, a flame opening 28 is provided in a peripheral portion of the match case by the simple expedient of removing portions of the front cover 24 and the peripheral rim 26.

Mounted for rotation within the outer casing 20 is a wheel or circular comb 30 supporting a plurality of matches 32 in radially extending relation about its periphery. Preferably the matches 32 are a type of "safety match" provided with combustible heads 44. The match supporting wheel 30 may be simply mounted for rotation on a pin 34 frictionally engaged in central openings 36 in each of the sides 22, 24 of the case. If desired, a spot of glue may be applied to the ends of the pin 34 to prevent its becoming unfastened from the case.

Although the wheel 30 may take any desired form, a preferred construction shown in Fig. 2 comprises a circular comb fabricated or cut from a single stiff piece of

The present invention relates to match cases adapted to carrying large numbers of individual matches, and particularly to means carried by the case whereby each of the matches may be rendered self-igniting.

The present invention was brought into being following a long search for a match case that could be simply and easily manipulated in one hand to provide for safe, effective ignition of matches carried within the case. The problem has been to find an economical and practical match case of this general type which, in addition to permitting effective competition with ordinary types of match cases, could be conveniently and safely carried in the pocket or purse of the user.

For years, little has been done to improve the packaging or the technique of use of the common "safety match." Customarily, such matches are bound in a "book" with the individual matches joined to form a "comb" positioned beneath a cover or folding flap portion of the book. An oxidizing agent such as potassium chlorate is generally contained in the heads of the matches while an igniting or flammable composition, usually red phosphorous, is formed into a striking surface secured to an outer surface of the book. To ignite one of the matches, the flap of the book must be opened and a match detached. The cover must then be replaced and the match ignited by striking its head against the phosphorous surface. As is common knowledge, it is virtually impossible to light the match except by holding the book in one hand and the match in the other. Thereafter, the match must be extinguished and disposed of in a safe manner. If the user is careless in discarding the match, considerable damage may result. It is a matter of grave public concern, for example, that untold millions in fire losses are caused by the discarding of improperly extinguished matches in wastebaskets, refuse cans, picnic areas, forests, warehouses, and in other highly flammable areas.

Generally stated, the present invention is directed to an entirely new concept in the use and packaging of cardboard safety matches whereby a match may be ignited safely and effectively by a single motion of one hand. Briefly, a device according to the invention comprises an outer casing, preferably disk-shaped, provided with a flame opening in its peripheral surface. Mounted for rotation within the casing is a wheel or other means supporting a plurality of matches about its periphery in such manner that head portions of the matches are capable of engaging a striking surface or other means for igniting the matches positioned adjacent the flame opening. Positioned for actuation externally of the casing is a mechanism for advancing individual matches in sequence against the striking surface and into the flame opening where the flame is available for lighting cigarettes, cigars or for other purposes. It is also contemplated that the flame opening be provided with shielding devices or insulation, preventing the ignition of other matches adjacent the flame opening.

Accordingly one object of the invention is to provide a means for packaging and igniting safety type matches

cardboard or laminate. If desired suitably shaped inner and outer spacer members 38 and 40 may be glued or otherwise secured to the sides of the wheel 30. This construction provides a convenient means for rigidly securing the matches 32 in a radially extending relation, and also for axially or laterally positioning the matches within a casing, for a purpose to be later explained.

Adjacent the flame opening 28, means are provided for igniting the matches 32 on movement of the matches into the flame opening. In the preferred embodiment of Fig. 1 to Fig. 4, a relatively durable striking surface 46 (of red phosphorus or other suitable material) is secured to a plate member 48 which may be pivotally mounted by staples, clamps or other means 49 adjacent the flame opening. Desirably the plate member 48 has at least one side, constructed for a reflective material, such as a polished metal or other suitable material, providing a heat-reflecting surface 50 shielding unused matches behind the striking surface from the heat of combustion in the flame opening. Flame-proof means may also be provided on the opposite side of the flame opening or on the back side 22 of the casing adjacent the opening. In the illustrated apparatus a thin strip of asbestos, metal or other material is stapled or otherwise secured to the inner surface of the casing 26, as at 54, so that a flap or protective curtain 52 is provided to prevent reignition of a previously ignited match. For a similar purpose a thin layer of asbestos or metal 56 may advantageously be secured to the back cover 22, as best seen in Fig. 2.

It is a feature of the invention that an actuating or advancing mechanism 60 is provided, preferably responsive to a single digital movement, to simultaneously advance a match against the striking surface 46 and into the flame opening 28. In the preferred embodiment illustrated, the actuating mechanism comprises a small wheel or rotary device 62 mounted for rotation in a slot 64 provided in the outer cover 24. As shown in Fig. 3, the wheel 62 rotates about a pin 66 secured to the inside of the cover by a spot of glue, staple or other device. Desirably the axis of the pin is on a line substantially perpendicular to the axis of the match carrying wheel 30 so that the member 62 is capable of rotating in a horizontal plane in abutment with side portions of the matches 32. Serrations or roughened areas 68 on the periphery of the member 62 serve to advance the matches against the striking surface 46 on rotation of the wheel member 62 in counterclockwise direction, as seen in Figs. 1 and 4.

As previously mentioned, spacer members 38, 40, may be employed to position the matches along the axis of the pin 34 a desired distance from the actuating wheel 62. In the form shown, the spacers are secured to the comb or wheel 30, and by engagement with sides 22, 24 of the case provide a certain amount of frictional drag which is only overcome by positive rotation of the actuating wheel 62, thereby preventing accidental movement of the matches. The spacers may also be employed to advantage, for advertising or other purposes, by providing a window 41 in the side of the case in which writing 42 on the exterior of the spacer 38 is clearly visible (Figs. 1 and 2).

To prevent accidental ignition of a match due to external jostling of the actuating wheel 62, a safety device 70 may be additionally provided. In the devices of Figs. 1 to 4, the mechanism of the safety device consists simply of a stop 72 slidably mounted on a pin or rivet 74 and provided with an extending finger bar 76. Preferably the rivet 74 is frictionally engaged by the slot 78 in the stop so that the stop will tend to remain in fixed sliding position.

To a worker skilled in the art it will be clear that the device just described provides a match case which for the first time enables a plurality of individual matches contained in the case to be sequentially ignited by manipulation of the case in just one hand. No longer is it necessary to free both hands each time it is desired to

light a cigarette, cigar, pipe or the like. Instead the device of the invention permits such every day routine operations to be performed in safety and in a single quick motion.

Figs. 6 to 8 illustrate a modified form of match case employing as the actuating or advancing mechanism a simple lever 80. In this embodiment, a cammed slot 82 in the peripheral portion 26a of the case provides for forward movements of the matches 32 while in positive engagement with the lever and thereafter permits the lever 80 to be disengaged from the matches for a return movement to its original match advancing position.

Referring specifically to Fig. 8, a suitable construction for the lever 80 comprises an actuating button 84 of sufficient size to prevent its slipping through the cammed slot 82. Extending downwardly from the button is a lever having a shank portion 86 terminating in a right angle extension 88. As indicated by the dotted line positions in Figs. 7 and 8, the lever extension 88 is adapted to pass between adjacent matches 32 for purposes of rotatively advancing the wheel 30. In use, forward movement of the lever 80 along the path indicated by the arrows 90 will act to advance a match against the striking surface 46a and into the flame opening 28a.

Preferably the slot 82 is provided with a cut-out or cammed portion 92 to permit return movements of the lever 80 in such manner that the lever extension 88 becomes disengaged from the matches 32. As indicated by the arrows 93, the lever moves from a position 94 between a first pair of adjacent matches 32 to a position at 96 from whence it can be subsequently moved along the path of arrow 98 to an advancing position 100 between the next pair of adjacent matches. When not in use, the lever 80 preferably is retained in a safe position in a recess 102 provided in the slot 82. It will be clear that this structure permits ignition of a match by a single movement of the thumb or forefinger in the direction of arrows 90, and return of the lever to an advancing position by a similar movement in the direction of the arrows 93.

In the device of Figs. 9 to 11, the actuating or advancing mechanism takes the form of a hinge means in which movement of the lever in one direction causes a positive advancing engagement of the lever with the matches 32 whereas movement of the lever in an opposite direction causes the hinge means to bend or close slightly to permit its repositioning between the next two adjacent matches. Specifically the advancing mechanism of Figs. 9 and 10 comprises a button or knob 110 adapted to protrude from a curved slot 111 in the side 24 of the casing. Extending inwardly from the knob 110 is a peg 112 mounting in axial relation a resilient member 114 preferably of a plastic or resinous composition, such as polyethylene. In the device illustrated the hinge extension 114 is curved in shape to resemble one half of a cylinder with its inner end 116 rigidly secured to the peg 112 by an adhesive or other suitable means. It will be understood that movement of the peg in the direction of the arrow 118 (Fig. 10) will cause the open edges of the hinge extension 114 to rigidly engage one of the matches 32, moving the match in a counterclockwise direction in the match case of Fig. 9. On the other hand, a reverse or backward movement of the knob 110 will cause the hinge extension 114 to bend as indicated by the dotted line position 120, enabling the advancing mechanism to return to an advancing position between the next pair of matches. In this way each of the matches 32 may be advanced against the striking surface 46 and into the flame opening 28. If desired, a spring 122 may be employed to accomplish the return movement of the button.

In Fig. 11 a further modification of a hinged type of advancing mechanism is illustrated. In this embodiment one portion 132 of a hinge, such as a conventional piano hinge, is rigidly secured to the advancing knob or button 130. The extending hinge portion 134 is normally biased

by the pressure of a relatively weak clip spring 136 into the full line position shown. In this position the hinged device 130 is capable of advancing a match against the striking surface 46 and into the flame opening of the match case. A return movement of the button 130 will cause portion 134 to move to the dotted line position 135 on contact with a match 32 until, eventually, it returns to the full line position between the next two adjacent matches in series. It will be understood, in the forms illustrated in Figs. 10 and 11, that the frictional drag of the wheel 30 and spacers 38 and 40 will normally be sufficient to overcome the pressure of the plaster hinge 114 or clip spring 136, and thereby prevent backward rotation of the matches.

To those skilled in the art to which this invention relates, many additional changes in construction and widely differing embodiments and applications of the invention will suggest themselves without departing from the spirit and scope of the invention. For example, instead of the striking surface being integral with the reflector surface as in Figs. 2, 6 and 9, a separate wedge-shaped striking surface 140 may be provided (Fig. 5) and adapted for use in conjunction with a separate reflector plate 142 pivotally mounted as before. If desired, the striking surface 140 could be removably mounted in the case, as by brackets or other convenient means (not shown). Also it is contemplated that a plurality of circular match cases of the type described might be mounted in tandem as in Fig. 12, with each unit being provided with an actuating mechanism 60 capable of operating the match carrying wheels 30. Accordingly, the disclosures and the description herein are purely illustrative and are not intended to be in any sense limiting.

I claim:

1. In a match case of a type particularly adapted to the ignition of a match by manipulation of the case in one hand, the combination comprising: an outer substantially disk-shaped casing provided with a flame opening in its peripheral surface; said casing mounting a

spindle axially thereof and a striking surface adjacent said flame opening; wheel means mounted for rotation on said spindle; a plurality of matches supported about the periphery of said wheel and extending radially outwardly therefrom; and actuating means carried by said casing and radially offset from the axis of said spindle for causing rotation of said wheel means, said means being capable of actuation by a single digital movement of one hand to force a match into said flame opening simultaneously with ignition of the match against said striking surface.

5 2. The device of claim 1 wherein said striking surface is provided with reflector means serving to prevent ignition of adjacent matches by the heat of combustion.

10 3. The device of claim 2 wherein flame proof means are additionally provided on a side of said flame opening opposite said striking surface, thereby serving to prevent re-ignition of a previously ignited match.

15 4. The device of claim 1 wherein said actuating means comprises a rotatable member having a roughened peripheral surface adapted to frictionally engage side portions of said matches, said member rotatably mounted on an axis in the plane of a side of said disk-shaped casing so as to extend on either side thereof.

20 5. The device of claim 1 wherein said actuating means comprises a reciprocable lever.

25 6. The device of claim 5 wherein said lever is capable of moving in a shaped slot while engaging a match and of subsequently moving in said slot to its original position without engaging a match.

30 7. The device of claim 5 wherein said lever includes hinge means allowing return of the lever without any substantial reverse movement of a match.
